CLAIM

What is claimed is the ornamental design for a table bar for wine tasting, as shown and described.

DESCRIPTION

FIG. 1 is a top perspective view of a table bar for wine tasting showing my new design;

FIG. 2 is a front view of the table bar of FIG. 1;

FIG. 3 is a rear view of the table bar of FIG. 1;

FIG. 4 is a top view of the table bar of FIG. 1;

FIG. 5 is a bottom view of the table bar of FIG. 1;

FIG. 6 is a left-side view of the table bar of FIG. 1; and,

FIG. 7 is a right-side view of the table bar of FIG. 1.

Broken lines are the features that illustrate environmental subject matter that forms no part of the claimed design.
